FLEXIBLE TOLL BARRIER

John A. T. Ellison, Seattle, Wash.

Application November 21, 1950, Serial No. 196,888

2 Claims. (Cl. 39—8)

1

The present invention relates to a toll barrier system and more particularly to a system wherein the barrier remains in a non-obstructing position unless passage thereby is attempted without first depositing a coin.

In recent years vehicle parking has become a perplexing dilemma in most urban areas even with the advent of the parking meters. Parking lots have not been a solution because the wages of an attendant combined with the rental for such a lot necessitate the charging of a parking rate which is prohibitively high for the average motorist. Some cities have attempted to eliminate the need for a parking lot attendant by installing a parking meter for each individual stall of the lot, but this requires that the parking lot be policed to insure that coins have been deposited in the meters in addition to the fact that such an installation has a high initial cost. To eliminate the need for such policing, coin-operated barriers for each individual stall have been proposed in the form of a gate which is locked in a closed position automatically by a vehicle entering the stall and which can be opened after the deposit of a coin to permit the vehicle to leave the stall. Such an arrangement is extremely expensive as well as being open to the objection that the gates are often prematurely closed by a vehicle maneuvering to get into the stalls.

Accordingly, it has appeared that the most workable solution would be an arrangement whereby a parking fee is deposited in a suitable meter either when the vehicle is entering or leaving the parking lot as such a system requires only a single barrier at the point of entry into the lot instead of a barrier for each individual stall. Furthermore, obvious advantages are enjoyed by a toll barrier system wherein the barrier is normally inactive, that is to say, a barrier which assumes an obstructing position only if a toll is not deposited at the required time.

Therefore, it is an object of the present invention to provide an improved toll barrier system of this general nature which is able to cope with all of the parking situations which might quite feasibly arise, as for example, the situation in which a vehicle is inadvertently driven into the parking lot when all of the parking stalls therein are already full, and the driver of this over-capacity vehicle desires to leave without the normal prerequisite of depositing a coin.

It is a further object of the invention to provide an improved barrier including a special power means for use in such a toll barrier system which will automatically close almost

instantaneously at the proper time and which can withstand, without damage, a considerable amount of force if engaged by a vehicle.

With the foregoing and other still more particular objects and advantages in view, the invention consists in the novel construction and in the adaptation and combination of parts hereinafter described and claimed.

In the accompanying drawings:

10 Fig. 1 is a plan view of the barrier of the present invention installed in a passageway and occupying a non-obstructing position.

Fig. 2 is a front elevational view of the barrier taken along the line 2—2 of Fig. 1 and with part 15 of the power means for raising the barrier exposed.

Fig. 3 is the front elevational view of Fig. 2 with the barrier shown in a raised obstructing position.

20 Figs. 4 and 5 are schematic plan views partly in section showing the position of the piston and valves when the barrier is in the non-obstructing and obstructing positions, respectively.

Fig. 6 is a transverse vertical sectional view 25 through one of the road switch units; and

Fig. 7 is a schematic view of the circuit for controlling the barrier.

Referring to the drawings, an arrangement is shown in which a single passageway is used both as an entrance and as an exit to a parking lot, the passageway being defined by curbings 10 spaced a sufficient distance apart to conveniently permit the passage of a vehicle therebetween. As a removable barrier for the passageway, I prefer to use a chain 11 extending from the eyed head of a standard 12 to a special upright housing 13, the said standard and the housing being anchored to the pavement at opposite sides of the passageway so that the chain traverses the latter. The housing 13 presents a vertical front leg 14 and a rearwardly sloping hollow leg 15 integral therewith, with the upper end of the housing being provided with a hawse pipe 16 communicating with the chamber in the sloping leg. It will be noted that within the sloping leg, adjacent its juncture with the front leg, there is provided a bottom pocket 29 serving as a chain locker. The lower end of the sloping leg has a cylinder 17 secured therein, and working in this cylinder is a piston 18 having an integral piston rod 20. This piston rod is journaled in a packing gland 19 at the forward end of the cylinder and presents an eye 21 at its free end to which one end of the barrier chain 11 is attached. Referring to Fig. 4 it will be noted that two pipes

22 and 23 are connected to the forward and rear end portions, respectively, of the cylinder and these pipes are cross-connected by a third pipe 24 continuing on beyond the pipe 23 to provide an exhaust pipe 25. A supply pipe 26 connecting with a supply of fluid under pressure, as for example, compressed air, joins pipes 22 and 24 at their juncture. It will be noted that the cross-connecting pipe 24 and the exhaust pipe 25 are provided with solenoid valves 27 and 28, respectively, of which the former is normally open and the latter normally closed. These valves are governed by a control circuit to be later explained. For the present it will suffice to say that when the solenoids of the valves are energized the valve 27 closes and the valve 28 opens. An alarm air-whistle 9 may be provided at the end of the exhaust pipe 25.

When the valves are as shown in Fig. 4 the pressurized fluid is supplied through pipes 22 and 23 to both sides of the piston 18, and since the forward working face of the latter is smaller in area than the rear face thereof the resulting pressure differential forces the piston to the forward end of the cylinder. The barrier chain is made of a length sufficient to drop freely onto the surface of the passageway between the curbs, as shown in Fig. 2, when the piston is assuming this forward position. When the solenoid valves 27 and 28 are energized and hence close and open, respectively, as shown in Fig. 5, the supply of pressurized fluid working against the rear face of the piston is dumped to the atmosphere through valve 28. The pressure on the forward face of the piston then exceeds that in the rear face and causes the piston to instantly move to the rear end of the cylinder. This piston movement causes the chain to be drawn through the hawse pipe and the stroke of the piston is sufficient to responsively raise the barrier chain, as shown in Fig. 3, to a height preferably as great as that of the wheel hub of the average vehicle.

An anchor chain 30 is anchored at the foot of the sloping leg and is housed therein with the other end being connected to the barrier chain. As can be seen in Fig. 2, the anchor chain is preferably of such a length that it will be drawn nearly taut when the barrier chain is in its inactive position. When the latter is raised, as in Fig. 3, the resulting slack links of the anchor chain stack in the chain locker. If the vehicle strikes the barrier when the latter occupies its raised obstructing position, the piston will be pulled to the forward end of the cylinder in which location the anchor chain will be drawn taut and will relieve the piston rod of any further pull should the motorist attempt to drive further. A diagonal side brace 31 is provided to reinforce the housing against the exerted pull of the vehicle should the above situation eventualize.

To aid in a ready understanding of the control circuit layout, the relays have been identified by a letter of the alphabet and each switch controlled by one of the relays has been given a designation on the drawing comprising a numeral followed by either a letter "B" or "M." The letter "B," intended to be suggestive of the word "broken," signifies that the switch is normally closed, and hence is broken or opened by the energizing of the respective relay. Likewise, the letter "M" is intended to be suggestive of the word "made" in order to signify that the switch is normally open, and hence is made or closed by the energizing of the respective relay. Accordingly, in the following discussion, the relay

switches will be identified by a letter prefix, signifying the relay controlling the particular switch, followed by a hyphen and a suffix comprising the aforesigned numeral and letter B or M designation of the switch in the drawing.

Before studying the control circuit it will be noted by referring to Fig. 1 that three road switch units, whose switches are designated R1, R2, and R3, are arranged in the passageway so as to be engaged sequentially by the wheels on the corresponding sides of entering and departing vehicles. As can be seen in Fig. 6, each unit is housed in a laterally extending road cavity 35 open at the top and presenting a short pedestal 36 at the bottom upon which the switch proper is mounted. The horizontal flanges of a pair of angle rails 37 are embedded in the road-bed at opposite sides of this cavity, and surmounting the switch proper is a channel bar 38 yieldingly supported by a pair of relatively stiff rubber webs 39 vulcanized to the angle bars and the channel bar. From this brief explanation it will be apparent that when a vehicle wheel engages the top of the channel bar, the bar is depressed into engagement with the underlying switch to close the latter and as soon as the channel is free of the wheel it is raised upwardly by the webs 39 to its normal surmounting position. The three road switch units are placed close enough together to preclude two of the switches from being closed simultaneously as by two different vehicles.

Referring now to the control circuit layout of Fig. 7, it is seen that the circuit to the solenoid valves 27 and 28 includes switches D-2M and J-1B, so that in order for this circuit to be completed, relay D must be energized while relay J is de-energized. Before proceeding to the individual circuits for these relays, a ready understanding thereof may be expedited by noting as a preview that since it is desired to have incoming vehicles enter freely into the parking lot, and outgoing vehicles leave only after the payment of a toll, the control circuit is arranged so that the energizing of relay J is made dependent upon the deposit of a coin in a suitable coin-box 33, and so that relay D is only energized during the exodus of an outgoing vehicle. This coin-box is carried on a standard adjacent the passageway and is arranged so that a switch 34 housed therein is closed each time a coin is deposited. The circuit for relay J is controlled by normally open switch H-2M, and relay H is energized to close this switch by the closing of the coin switch 34.

Reverting to relay D, the energizing circuit for this relay includes switches F-1M and E-1M and thus is completed when relays E and F are both energized. The energizing circuits for these relays include, respectively, road switches R2 and R3, and since these road switches are only closed 60 instantaneously as a vehicle wheel passes thereover, holding circuits are provided to keep relays E and F energized after the road switches R3 and R2 are closed by a departing vehicle and until road switch R1 is closed. Continuing to these 65 holding circuits, relay E is kept energized by a circuit through switches D-1M and G-1B, and relay F is kept energized by a circuit including switches F-2M and C-2B. Relay C, which opens the latter switch, is energized by an outgoing vehicle through a circuit including switches J-2M and A-1M. The first of these two switches, as will later appear from an explanation of the holding circuit for relay J, remains closed after the deposit of a coin until the rear wheels of the outgoing vehicle cross road switch R1. The closing

of this road switch always energizes relay A and hence causes the closing of switch A-1M, so that relay C is always energized, and hence relay F is always de-energized when an outgoing vehicle closes road switch R1. While this road switch is thus closed, relay D remains energized for a purpose to be later explained, through a holding circuit including switches E-3M, A-3M, and E-1M. Accordingly, the instant that road switch R1 then opens causing switch A-3M to open by the resulting de-energizing of relay A, relay D is deenergized. This opens switch D-1M and hence also de-energizes relay E. Relay C has a holding circuit through switches C-1M and F-1B, the latter switch and the afore-mentioned switch C-2B functioning to prevent relays C and F from being energized at the same time. Since relay J is normally not energized, and hence since switch J-2M is normally not closed to complete the afore-said energizing circuit for relay C when a vehicle is entering the parking lot, a switch which is always open when an incoming vehicle closes road switch R1 is provided in parallel with switch J-2M so that relay C will always be energized by such incoming vehicle, and namely switch D-4B. This arrangement precludes relay F from being energized when an incoming vehicle closes road switch R2 regardless of which direction the preceding vehicle was traveling, and hence assures that such incoming vehicle cannot cause relay D to be energized.

Relays K, L, and N, and ratchet relay unit 40 are provided in the control circuit to keep relay J energized after a coin has been deposited and until both the front and rear wheels of a vehicle have passed over the three road switches. Otherwise a second coin would have to be inserted in the meter to prevent the barrier from being activated when the rear wheel of a departing vehicle closes road switch R2. The ratchet relay unit is shown diagrammatically in Fig. 7 and functions to alternately open and close a switch 41. It comprises two wheels 42 and 43 coupled together to turn in unison, the former being simply a ratchet wheel and the latter being a lantern wheel in which the circumferential length of the trundles, designated by 44, corresponds to the openings between the trundles. The switch 41 is spring-urged to an open position and is arranged to be activated by the trundles into circuit closing engagement with a terminal 45. The ratchet wheel 42 is operated by a dog 46 activated in turn by a solenoid 47. In the drawing, switch 41 is shown in circuit-closing position, and namely a position whereat it rests in one of the openings between the trundles 44, and it can be readily seen that when the ratchet wheel 42 is advanced one step, the switch will then be raised by the next trundle so as to close the switch. The next solenoid-responsive movement of the ratchet wheel 42 perforce again opens the switch. Thus it is seen that the switch 41 opens every second time that the solenoid 47 is energized.

This solenoid 47 has two energizing circuits connected in parallel, one including switches N-2M and H-1M, and the other being controlled by switch K-4M. The first of these circuits is provided to insure that switch 41 will always be in an open position after a coin is deposited even if perchance in a closed position immediately prior to such deposit because of some irregularity in the sequence of operation of the control system. This office of such circuit is performed by way of the fact that whenever switch 41 is in such a closed position, the energizing circuit for relay

N is completed and hence switch N-2M is closed. The insertion of the coin causes relay H to energize and hence insures that switch H-2M is closed to complete the energizing circuit for the ratchet relay 42, thus causing switch 41 to reopen.

The second energizing circuit for the solenoid 47 that is to say, the circuit including switch K-4M, is solely dependent upon relay K for completion. Normally closed switches D-4M and A-4M are included in the energizing circuit for relay K and hence such circuit is completed only when relays D and A are both energized. As explained earlier, these two relays are both energized only while road switch R1 is closed by an outgoing vehicle. Thus it is seen that the ratchet switch 41 is closed and relay N energized whenever the front wheels of a departing vehicle cross the three road switches. The energizing circuit for relay L includes switches K-1M and normally closed switch H-1B so that this relay is also energized when relay K is energized. As mentioned earlier, the holding circuit for relay J includes switch L-1B. However, switch N-1M is wired in parallel with this switch so that when the latter is opened by the energizing of relay L, relay J remains energized by the alternative holding circuit through switch N-1M. Switch A-2M, which is momentarily closed when road switch R1 is closed, is also wired in parallel with switch L-1B so that it carries the load during the split second that the holding circuit for relay J is shifting from switch L-1B to switch M-1M. It will be noted that relay L remains energized after road switch R1 reopens through a holding circuit including switches H-1B, J-1M, and L-1M.

From the foregoing discussion it is seen that relays J, L, and N remain energized while the rear wheels of a departing vehicle pass road switches R1 and R2. When the rear wheels reach road switch R1, relay K is again energized so that the energizing circuit to the solenoid 47 through switch K-4M is completed. This results in the stepping of the ratchet relay unit so that switch 41 is opened and relay N is de-energized. At this point the holding circuit for relay J transfers from switch N-1M to switch K-3M and hence relay L will remain energized until relay K is de-energized. The latter occurs at the instant that road switch R1 reopens upon the completed exit of the departing vehicle because this reopening results in the opening of switch A-4M. At this time relays L, D, and E are also de-energized due to the opening of switches J-1M, A-3M and D-1M, respectively.

Relay G is included in the circuit to provide for the circumstance in which a motorist backs over the road switches in the exit direction while parking and hence accidentally causes the barrier to be activated. As afore-mentioned, the holding circuit for relay E includes switch G-1B, and it will be noted that the energizing circuit for relay G includes road switch R3 and switch D-3M, the latter being in a closed position whenever the barrier is activated. Accordingly, when the motorist drives again over road switch R3, relay G will be energized, and this will open switch G-1B and hence open the holding circuit for relay E. Since the circuit to the circuit for the solenoid valves is open whenever relay E is de-energized, the barrier will assume its inactive position and vehicles can again enter the parking lot without necessitating the deposit of a coin.

The inclusion of switch D-4M in the energizing circuit of relay K, which in turn, through switch K-4M, controls the energizing of the solenoid 47,

provides for the possible situation in which the driver of an outgoing vehicle, because of a traffic jam or some other circumstance, permits an incoming vehicle to enter the parking lot after he has deposited a coin and before he has effected an exit. In such a situation, no harm results because relay D is never energized, and hence switch D-4M is never closed, due to the closing of the road switches by the incoming vehicle. In fact, even if an outgoing motorist, after depositing the required coin, drives as far as the second road switch and then backs up to allow another vehicle to enter, he will not have to deposit a second coin to leave the lot because when he closes road switch R3 while backing up, relay D will be de-energized due to the resultant energizing of relay G as above described.

In order to provide for the possible situation in which a vehicle is driven into the parking lot after the lot is already full, and hence is entitled to depart without the depositing of a coin as a prerequisite, a normally open switch 50 wired in parallel with the coin-box switch 34 is provided along with a device for closing this switch while such an over-capacity situation is present. This device will be hereinafter termed a computer and can comprise, as shown schematically in Fig. 7, two ratchet wheels 51 and 52 coupled to a third wheel 53 presenting a cam finger 54. These ratchet wheels have their teeth directed for opposite rotation and are driven by pivoted solenoids 55 and 56, respectively, through dogs 57 and 58. The energizing circuit for the first of these two solenoids includes switches E-2M, C-2M and J-2B, and hence is completed when road switch R2 is closed in the incoming direction at which time relays E and C are energized and relay J is de-energized. Solenoid 56, on the other hand is controlled by relay K for it is actuated through normally open switch K-2M, and as afore-explained, this relay is only energized when road switch R1 is closed by an outgoing vehicle. Since both the front and rear wheels of an entering or outgoing vehicle cross the road switches, the ratchet wheels 51 and 52 will respectively progress two teeth in the clockwise or counter-clockwise direction, each time a vehicle enters or leaves the lot. This will cause the third wheel to turn one way or the other with the over-all progress of the latter in the clockwise direction being governed by the mathematical difference between the number of vehicles entering and leaving the parking lot. By this arrangement the wheels can be set so that the finger 54 will progress to the position shown in Fig. 7 when the said mathematical difference equals the parking capacity of the lot. With such a setting the act of an over-capacity vehicle entering the lot, will cause the finger to close the switch 50 and the switch will remain closed until the vehicle leaves the lot and causes the finger to retreat from beneath the switch.

If it is desired to have a separate entrance and exit for the parking lot, the exit can be provided with the arrangement above described, and this arrangement can be modified for the entrance

by eliminating the coin-box and associated switch 34. This modification would make it impossible for a vehicle to depart through the entrance to the lot.

5 It is thought that the invention, and its advantages, will have been clearly understood from the foregoing detailed description of the preferred illustrated embodiment. It is self-evident that changes from the illustrated and described 10 embodiment may be resorted to without departing from the spirit of the invention and it is accordingly my intention that no limitations be implied and that the hereto annexed claims be given a scope fully commensurate with the broadest interpretation to which the employed language admits.

What I claim is:

1. In a barrier system, a flexible barrier adapted to be anchored at both of its ends with the major part of its length extending across a passageway and movable from a lowered slackened non-obstructing position to and from an elevated non-slackened obstructing position, and power means connected to the barrier at a location adjacent one of its ends for taking up and letting out slack between said location and the other end of the barrier and, respectively, letting out and taking up slack between said location and the adjacent end of the barrier, said power being arranged and said location being such that there is no slack in the portion of the barrier between the said location and the adjacent end of the barrier when the barrier is in its said slackened non-obstructing position so that the anchored 35 ends of the barrier will take the entire load of an externally applied force tensioning the barrier and directed endwise of the passageway.

2. A barrier comprising a flexible member of sufficient length to extend across a passageway, 40 said member having two ends one of which is fixed, operating means comprising a cylinder and a piston and rod therein, said cylinder being fixed and said rod being attached to the second end of said member, fluid pressure means operatively connected to said cylinder on opposite sides of said piston, the pressure means on the rod side of the piston being constantly open and the pressure means on the other side of the piston being provided with a controllable valve, whereby the 45 flexible member may be slackened at will.

JOHN A. T. ELLISON.
